SHEET DECURLING APPARATUS

Lynn O. Hayes, St. Louis, Mo., assignor to F. L. Smithe Machine Co., Inc., New York, N. Y., a corporation of New York

Application October 24, 1941, Serial No. 416,293

16 Claims. (Cl. 93—61)

This invention relates to decurlers suitable for taking the curl out of sheet material such as paper, and particularly for correcting the curling effect of dried adhesive material located on one side of the paper. This is accomplished in general by drawing the sheet over a decurling edge engaging the convex side of the paper; and the decurling action is materially affected by the angle at which the sheet is drawn across such edge. The appropriate bend may be imparted to the sheet by passing it under a guide member located immediately in advance of the decurling edge; and may be varied by adjusting the spacing of the guide member and edge in a direction transverse to the sheet path.

A feature of the invention is the provision of a construction in which the spacing of said member and edge may also be adjusted longitudinally of the sheet path. It has been found that the provision of such longitudinal adjustment improves the decurling action with certain types of sheet material, and particularly paper varying in thickness, stiffness or strength, making the same device effective for decurling a variety of types of stock.

A purpose of the invention is to provide a decurler that is especially effective in decurling the gummed closure flaps of envelopes, and which is suitable for incorporation in continuous envelope folding machines. Such flaps are customarily tapered, and the curling effect of the dried gum is of course primarily restricted to the gummed area, which in the type of envelope most widely used is a strip extending along the tapered margin of the flap, producing a V-shaped curled zone that presents special decurling problems. In decurling envelope flaps the closure flap is initially bent over the decurling edge along a line adjacent and parallel to the junction of the flap with the body, and is drawn across the edge with a constantly decreasing width of the flap engaging the guide member and said edge, presenting a special problem in obtaining the proper decurling action in all parts of the flap, which is met by this invention.

The disclosed features are especially effective for decurling envelope flaps in this manner, and the device is constructed so that it may be incorporated in an envelope folding machine at any one of several stages in the folding cycle. It has been found to be especially advantageous to locate the device at a point where the side flaps of the blank have been folded in, but the bottom flap has not been gummed or folded.

Further objects of the invention include the

provision of a simple and strong construction which may be readily attached to standard types of sheet handling apparatus, such as envelope folding machines.

5 Other objects and advantages of the invention will appear from the following description considered in connection with the accompanying drawings in which

Fig. 1 is a plan view of a decurling device mounted on a standard type of envelope folding machine;

Fig. 2 is a transverse vertical section through the device on line 2—2 of Fig. 1;

Fig. 3 is a similar but more diagrammatic view 15 with the device in decurling position; and

Fig. 4 is a detail of an adjusting construction.

The invention is disclosed in its application to a machine for folding envelope blanks having closure flaps the margins of which have been provided with gum in the usual manner. Such gum when dried tends to produce a substantial curl which prevents the folded envelopes from lying as flat as is desired, the inturned edges likewise tending to mark the body of the envelope.

25 A machine of this type is disclosed in the patent to Winkler et al. No. 1,396,906.

Portions of such a machine, illustrated diagrammatically in Fig. 1, include a frame 10, driven rollers 11 and 12 and cooperating pressure rollers 13 and 14 arranged to convey an envelope blank 15, having a bottom flap 16 and a closure flap 17, through a decurling device, the blank being supported by table 18. Said table includes a feed section 20 extending to the bight between rollers 11 and 13, intermediate sections 21 and 22 located between the two pairs of rollers, and discharge section 23 arranged to receive blanks discharged by rollers 12 and 14, said table sections being arranged substantially in the same plane 30 passing through the bights between the two sets of rollers.

The decurling device is supported on posts 25 carried by frame 10, and consists of a stationary guide assembly and a movable decurling edge unit.

45 The guide assembly is mounted on supports 26 carried by posts 25 and includes guide bar 27 extending across the path of blanks 15 at right-angles to the direction of travel of the blanks immediately above their normal path.

50 A suitable construction is provided for mounting bar 27 for adjustment both transversely to and longitudinally of the direction of blank travel; and in the preferred construction disclosed such mounting includes a yieldable support for the bar 27. This is advantageously ac-

complished by providing at each side of the path of the blanks an adjustable front stop against which the bar 27 is held by spring means, and a vertically adjustable member engaged by bar 27. Specifically, the construction at each side of the blank path includes a standard 30 mounted on support 26 carrying a rearwardly extending arm 31 pivotally supported by pivot pin 32 and engaging guide bar 27. A suitable arrangement is provided for adjusting arm 31 about its pivot, the form disclosed comprising a post 33 on support 26 carrying an extension plate 34 projecting over arm 31. Adjusting screw 35 threaded through plate 34 engages arm 31 and is restrained against accidental rotation caused by vibration or the like by coil spring 36 surrounding the shank of the screw. In the form illustrated bar 27 is not positively held by arm 31, but is held yieldingly against the lower face of said arm, as by coil spring 37 seated in socket 38 in support 26 and bearing against the lower face of bar 27. In this specific form arm 31 is in turn pressed upwardly by bar 27, and bears against the lower end of screw 35 which serves as an adjusting stop for regulating the spacing of guide bar 27 and the decurling edge hereafter described, in a direction transverse to the path of the blanks.

A portion of each end of bar 27 is advantageously arranged to engage an arm 31 to limit endwise movement of the bar. This is conveniently accomplished by constructing bar 27 in the form of a flat rectangular strip as shown, with its ends terminating adjacent arms 31 and extending above the lower faces of said arms. Pins 39 extending from the ends of bar 27 bear against the lower faces of arms 31 and are maintained in engagement therewith by springs 37.

A suitable arrangement is provided for adjusting bar 27 longitudinally of the direction of blank movement. In the form disclosed this includes a support plate 43 adjacent each end of the bar 27 against which the front face of the bar is normally held, plate 43 being provided with an integral tail plate 44 (Fig. 4) having a slot 45 parallel to the direction of blank travel and slidably fitting a post 46 on support 26. Eccentric 47 rotatable on post 46 bears against the rear face of support plate 43 and is held in adjusted position on the post by set screw 48.

An arrangement is provided for holding bar 27 in engagement with support plate 43. The disclosed construction for this purpose includes a plunger 50 slidable in bore 51 in post 33, held in engagement with the rear face of bar 27 by coil spring 52 in bore 51 bearing against pressure adjusting screw 53 threaded into the rear end of said bore.

It will be understood that the described arrangements for supporting guide bar 27 are duplicated at opposite ends of the bar outside of the path of the blanks 15.

The decurling edge unit comprises a decurling bar 55 extending transversely to and slightly below the path of the blanks when in inoperative position, and movable upwardly to project across said path slightly beyond guide bar 27 in the direction of blank travel when in operative position. The disclosed arrangement for moving bar 55 into and out of operative position includes a pair of rock arms 56 connected to the ends of bar 55, arms 56 being supported by pivots 57 on posts 25. Each arm 56 carries a cam roller 58 bearing against a face cam 59 fixed to the shaft 60 of roller 11, roller 58 being held on cam 59 throughout the cycle of operations by coil spring 61 extending from the end of arm 56 to frame

10. The intermediate table sections 21 and 22 are suitably held in position, as by support bars 62 mounted on supports 26.

5 The sheet engaging surfaces of decurling bar 55, guide bar 27 and table section 21 are suitably proportioned and positioned to operate in the manner heretofore set forth. The lower face 63 of guide bar 27 is advantageously parallel to the upper face of table section 21 and forms a guide edge 64 at its intersection with the front face 65 of the guide bar. Decurling bar 55 is provided with a decurling edge 66 at the intersection of its rear face 67 with its top face 68, the latter being advantageously inclined at an acute angle to face 67 appropriate to avoid contact of the blank 15 with top face 68 after passing the decurling edge 66.

10 With this arrangement the angle at which the blank is bent about edge 66 is determined by the angle between the portion of the blank extending from guide edge 64 to decurling edge 66 and the portion of the blank extending from the latter edge to the bight of rolls 12 and 14. Moreover, the paper will not ordinarily form an absolutely sharp angle when passing over edge 66, but will form a bend having a curvature which will depend upon the characteristics of the paper, and particularly its stiffness and thickness, as well as the tension upon the paper at this point. Such curvature, and the resulting decurling effect, will vary if the paper does not pass in a uniform plane to edge 66 from edge 64. Uniformity at the latter point is assured by extending table section 21 substantially to edge 64. Moreover, the sharpness of the bend about the latter edge will be influenced by the spacing between guide edge 64 and the face of table section 21.

20 While the tension of spring 61 is normally sufficient to maintain rollers 58 in engagement with cams 59, the tension of said springs may also be such that decurling bar 55 can yield downwardly under particularly excessive strain to avoid rupture of the sheet in the manner already set forth.

30 I have described what I believe to be the best embodiments of my invention. I do not wish, however, to be confined to the embodiments shown, but what I desire to cover by Letters 35 Patent is set forth in the appended claims.

40 I claim:

1. Sheet decurling apparatus comprising a decurling member and a guide member engaging opposite sides of a traveling sheet, arranged to bend the sheet across the decurling member, and an adjusting construction for varying the spacing of the decurling member and the guide member in the direction of sheet travel.

2. Sheet decurling apparatus comprising, in combination, means defining substantially a path of sheet travel, a decurling member and a guide member engaging opposite sides of a traveling sheet arranged to bend the sheet across the decurling member, and means yieldably maintaining said members in predetermined spaced relation longitudinally of the sheet path, including a stop engaged by one of the members and a spring arranged to bias said member toward the other member and against the stop.

3. Sheet decurling apparatus as set forth in claim 2 in which the stop and spring act upon the guide member, said guide member being biased in the direction of sheet travel against the stop.

4. Sheet decurling apparatus comprising a

decurling member movable into engagement with one side of a traveling sheet, a guide member located in advance of the decurling member at the opposite side of the sheet in position to guide the sheet at an angle about the decurling member, and a support for the guide member including an adjusting device for varying the spacing of the guide member and the decurling member in the direction of sheet travel.

5. Sheet decurling apparatus as set forth in claim 4 in which the guide member support includes a stop and a spring device for yieldably biasing the guide member against the stop.

6. Sheet decurling apparatus as set forth in claim 4 including a device for adjusting the spacing of the sheet engaging portions of the guide member and decurling member transversely to the direction of sheet travel.

7. Sheet decurling apparatus as set forth in claim 4 including a device for adjusting the spacing of the sheet engaging portions of the guide member and the decurling member transversely to the direction of sheet travel, said latter adjusting device comprising an adjustable stop and a spring device arranged to bias the guide member toward the stop.

8. Sheet decurling apparatus comprising a decurling member arranged to engage one side of a traveling sheet, a guide member in advance of the decurling member arranged to engage the other side of the sheet and to bend the sheet across the decurling member, and a floating support for the guide member including a stop construction and a spring construction arranged to bias the guide bar against the stop construction in the direction of sheet travel and also transversely to the direction of sheet travel.

9. Sheet decurling apparatus comprising sheet advancing mechanism, a decurling member at one side of the sheet path having a decurling edge formed by the intersection of two adjacent surfaces of the decurling member at an acute angle to one another, a guide member at the other side of the sheet path in advance of the decurling member, said members being spaced from said path in inoperative position, one of the members being movable transversely to the path and toward the other member lengthwise of the path into operative position overlapping the other member and in proximity thereto longitudinally of the path to bend the sheet across the decurling member, and mechanism for shifting said movable member into and out of operative position, including a rocker arm to which said movable member is fixed and actuating mechanism for rocking the rocker arm.

10. Apparatus for decurling traveling sheets comprising a decurling member operable to and from a position for engaging the convex side of the sheet, a stationary guide member engaging the concave side of the sheet in advance of the decurling member arranged to bend the sheet across the decurling member, and a guide engaging the convex side of the sheet in advance of the guide member and in fixed relation thereto arranged to guide the sheet to the guide member.

11. Sheet decurling apparatus as set forth in claim 10 in which the sheet guide comprises a sheet supporting table.

12. Sheet decurling apparatus as set forth in claim 10 in which the guide member and the sheet guide are relatively adjustable in a direction transverse to the sheet path.

5. 13. Apparatus for decurling traveling sheets comprising a table structure, mechanism for advancing sheets successively including a pair of sheet advancing rolls and a pair of rolls arranged to feed sheets to the advancing rolls along the

10 table structure, a sheet decurling device including a decurling member movable between spaced portions of the table structure into engagement with the lower face of a sheet, a stationary guide member having a lower face located above the

15 table structure and adjacent thereto in advance of the decurling member, arranged to bend a sheet across the decurling member, and actuating mechanism for moving the decurling member upward into engagement with the trailing portion of a sheet and across the plane of the lower face of the guide member after the sheet has been fed across the table structure to the advancing rolls and released by the feed rolls.

20 14. An envelope forming machine comprising side flap folding mechanism, bottom flap gumming mechanism, bottom flap folding mechanism, top flap folding mechanism, conveying mechanism for passing envelope blanks in succession through said folding and gumming mechanisms

25 with the top flap trailing, including two adjacent pairs of rolls located between the side flap folding mechanism and the bottom flap gumming mechanism, and a decurling device located between said pairs of rolls including a decurling member arranged to engage the convex side of the closure flap, a guide member arranged to engage the concave side of the closure flap in advance of the decurling member to maintain said flap in bent position across the decurling member

30 when in operative position, actuating mechanism for shifting said members into and out of operative position, and an adjusting construction for varying the spacing of the guide member and the decurling member in the direction of

35 sheet travel.

15. Sheet decurling apparatus comprising registering decurling members on opposite sides of the plane of a traveling sheet, actuating mechanism for moving a decurling member into decurling position adjacent to and overlapping the other member, a support on which said other member is mounted in stationary position, and a device for adjusting said stationary member

40 on the support in a direction longitudinal to the travel of the sheet, thereby varying the longitudinal spacing between the members in decurling position.

16. Sheet decurling apparatus comprising a stationary decurling member located at one side of the plane of a traveling sheet, a registering movable decurling member at the other side of said plane, actuating mechanism for shifting the movable member into decurling position adjacent to and overlapping the stationary member, and a

45 device for adjusting the spacing of said members in decurling position in the direction of sheet travel.

LYNN O. HAYES.
